UNITED STATES PATENT OFFICE.

JOSEPH MEINECKE, OF PAIA MAUI, TERRITORY OF HAWAII.

CANE-SUGAR MILL.

1,401,095.

Specification of Letters Patent. Patented Dec. 20, 1921.

Application filed July 7, 1920. Serial No. 394,456.

To all whom it may concern:

Be it known that I, JOSEPH MEINECKE, a citizen of the United States, and a resident of Paia Maui, Territory of Hawaii, have invented certain new and useful Improvements in Cane-Sugar Mills, of which the following is a specification.

This invention relates to improvements in cane sugar mills and more particularly to 10 an improved intermediate cane chute for transferring or conveying the bagasse from one mill to the other.

Heretofore, in the art of sugar mills, devices have been constructed for conveying 15 the bagasse from one mill to the other, these devices being in the nature of endless conveyers employing chains, sprockets and bars or slats connecting the chains to carry the bagasse from one mill to the other between 20 adjacent macerating rollers of the mills, scrapers being employed at each end, but these devices having been found objectionable due to the constant delays from breakage and injury to the parts at a considerable 25 cost of production and upkeep or maintenance. Effort has also been made to push or use pressure in carrying the bagasse from one mill to the other but is objectionable and the devices found inefficient and 30 discarded, owing to the fact that the enormous pressure of the bagasse in being pushed from one mill to the other, bent the chute and bars of steel, forming reinforcing means for the same. Such a chute was 35 curved and associated with macerating scrapers but resulted in the material packing up therein and rendering operation impossible.

The present invention has for its objects 40 to provide an improved chute by which the bagasse may be properly pushed or conveyed from one mill to the other, without injury or distortion from the pressure, as well as obviating the necessity of employing 45 a conveyer of the slatted and belt type and eliminating the large number of complicated parts and expensive construction together with all movable parts employed in the old chain type of conveyer, and there- 50 by avoiding constant annoyance from the necessity of repairs, reducing the cost of construction and installation, as well as maintenance and upkeep, eliminating all rollers and other movable parts.

55 I am aware of prior Patents Nos. 1,191,826, 1,209,618 and 1,204,814, as well as

of the devices employing a curved chute or movable parts for the purpose but my device is an improvement thereof, in view of its simplicity of construction, economical 60 production and durability in use, as well as efficiency, for the purposes stated, avoiding all delays due to breakage of the carriers and slat conveyers and resulting in a clean mill at all times with a more efficient product 65 and increased output without any especial attention, the device being also constructed so as to facilitate cleaning when the mill is shut down at the end of the week or at any other time. 70

I obtain these objects by the device illustrated and other and further objects of my invention will become readily apparent to persons skilled in the art, from a consideration of the following description when 75 taken in conjunction with the accompanying drawings, in which:—

Figure 1 is a side elevation showing the improved intermediate cane chute as applied to a sugar cane mill and in transferring the bagasse from one mill to the other between the macerating rollers thereof with which scrapers are employed,

Fig. 2 is an enlarged fragmentary vertical sectional view of the discharge end of the 85 chute, and

Fig. 3 is a transverse sectional view taken on the line 3—3 of Fig. 2.

Referring to the drawings in detail, in which like reference characters designate 90 corresponding parts throughout the several views, the numeral 10 designates a sugar cane mill having the usual macerating rollers and 11 an adjacent mill of a plurality or series properly spaced apart to macerate 95 the cane or like material, the expressing rollers thereof being designated at 12. The conveying apparatus is arranged between the adjacent mills for the purpose of feeding the bagasse from one mill to the other 100 and in the present instance the improved chute is designated generally at 13. This chute is oppositely inclined between the discharge end of the preceding mill and the feed end of the succeeding mill, and includes a bottom plate 14 arranged at an angle of from 30 to 45°, preferably 45° from the horizontal at the feed end of the succeeding mill, said plate being disposed in an inclined position and having inclined and 105 joined therewith to extend in an opposite direction, a bottom plate 15, which like the

bottom plate 14 and other parts of the chute, is constructed of sheet metal. The bottom plate 15 extends at an angle of from 30 to 35°, preferably 30° from the horizontal at 5 and from the discharge end of the preceding mill, so as to give less inclination at the discharge end of the mill or greater inclination at the discharge end of the chute and obviate excessive pressure attendant with 10 macerating mills and in employing the ordinary curved chute with macerating scrapers as referred to in connection with the patents hereinbefore recited.

The chute is supported at either side upon 15 suitable structure of the frames of the mills, side plates 16 and 17, being provided for this purpose and reinforced by braces 18 and 19 in conjunction with the actuating parts including arms 20 and the adjustable turn-buckle toggle joints or connection rods 21 arranged at the discharge end of the chute.

It will thus be seen that the chute or conduit has the bottom plates thereof arranged at a certain inclination with respect to the 25 horizontal and to each other so that the bagasse is pushed up one side and down the other to withstand the enormous attendant pressure, the apex of the chute being substantially equidistant between the two mills 30 but with a greater inclination at the feed end of the mill than at the discharge end or at the discharge end of the chute and at the feed end. At the discharge end of the preceding mill or feed end of the chute, 35 scrapers 22 are provided which are cast in and have connections with the arms 20 through the pivots 23 allowing for the necessary contact, adjustment and tensional regulation through the medium of the turn-buckle connections 21.

The sides of the chute are designated at 24, the side and bottom portions inclining from the transverse line of the apex of the chute to the opposite side and one of said 45 sides, namely, the side having the plate 15, being provided with a cover plate 25 at the discharge end of the preceding mill or feed end of the chute which is removably bolted in position as indicated at 26, twelve of such 50 bolts being employed so as to render removal of the cover and cleaning of the chute readily possible. The cover is provided with a flange 27 at its side edges to render the attachment convenient and said cover is 55 suitably reinforced transversely as indicated at 28, while the intermediate portions of the sides of the chute are provided with horizontal supporting brackets or flanges 29 bolted in position and supporting the macerating pipes 30 leading from a suitable 60 source of water supply, so that the bagasse is sprinkled as it comes out of the chute and is discharged down the inclined side 14, the top of which is open. Thus, the bagasse of 65 mass is taken at the discharge side of the

preceding mill or feed end of the chute adjacent to the scrapers and shoved up the bottom of the chute which is covered or closed and which has the lesser inclination, the bottom portion or plate delivering the 70 bagasse in an upward direction and on to the inclined portion or bottom plate 14 of greater inclination so that the discharge is freed of pressure, thus delivering the bagasse to the succeeding mill without any 75 movable parts or excessive pressure causing destruction, distortion or injury to the chute. The bagasse is furthermore delivered upwardly or in an upward direction with a gradual taper and no curves or a completely 80 closed chute is employed or necessary and therefore attendant objections to such devices are overcome. The material or bagasse slides down the discharge chute or 85 bottom plate without any assistance and the macerating water is applied as the material comes out of the chute on its downward movement. That is, there is no pressure on the bagasse as the chute is gradually tapered and there is only a pressure tending to shove 90 the material from the discharge roller into the receiving mill, thus avoiding all movable parts or alterations in the design of the mill with obvious advantages manifest to anyone acquainted with the art. Also, by 95 reason of the construction provided there is considerable clearance beneath the chute and this is an important factor in the operation of the mills. It is also to be noted that the top portion or cover 25 extends at an angle 100 from 30 to 35° from the horizontal, preferably 35° when the bottom plate 15 is disposed at an angle of 30° from the horizontal, causing the covered portion of the chute to be wider at its discharge end than at its 105 receiving end adjacent to the scrapers, so as to free the pressure which would otherwise be attendant in the conveyance of the bagasse.

In view of the foregoing, it is thought 110 that the operation of the device will be readily understood and in view of the simplicity and practical value, that it will commend itself to those skilled in the art.

Having thus described my invention, what 115 I claim is:—

1. An intermediate feed chute for sugar mills comprising oppositely inclined portions disposed at different inclinations, said portions being flat and means for supplying 120 macerating fluid at the apex of the chute.

2. A chute of the character described for disposition between spaced mills of a cane sugar mill or the like, comprising oppositely sloping bottom portions, side portions therefor adapted to conform to the rollers of the mill, the bottom portion at the receiving side being provided with a removable cover and the bottom portion at the discharge side of the chute being uncovered, and means for 130

supplying macerating fluid at the apex portion of the chute whereby the bagasse may expand unrestrained by the cover.

3. A chute of the character described comprising a trough-like structure open at the top and having oppositely inclined bottom portions, the receiving side being of less inclination than the discharge side, a cover at the receiving end portion of the chute, said chute being of tapered formation and being enlarged in width from the receiving end toward the apex portion.

4. A chute of the class described comprising oppositely inclined flat rectilinear bottom plates disposed in angular relation to form a straight line across the apex, side portions thereof, a water supply pipe supported above the top portion of the chute to supply water downwardly to the bagasse and a cover over the plate at the receiving side of the chute and converging toward the receiving end thereof.

5. An intermediate feed chute for sugar cane mills or the like comprising oppositely inclined bottom portions disposed at different inclinations, the inclination of the discharge side of the chute being such as to cause the automatic discharge of the material fed thereon from the feed side free of the pressure of the material behind it, said chute being in the form of an open trough and enlarged from the receiving end toward the discharge end, a cover over the receiving end of the chute and means for supplying water to the bagasse at the apex of the chute.

6. The combination with spaced roller mills in a sugar cane mill; of an intermediate chute comprising opposed plates having portions fitting said rollers, oppositely

inclined bottom plates between said opposed plates and connected thereto, said bottom plates being disposed in angular relation to each other, the plate at the discharge side of one mill and at the feed side of the chute being disposed at a lesser inclination than the bottom plate at the other side, a connecting plate between the opposed plates forming the sides of the chute and over the plate of lesser inclination, the opposite plate being uncovered, and macerating pipes supported at the top of said opposed side plates.

7. A chute of the character described for disposition between spaced mills of a cane sugar mill or the like, comprising oppositely sloping bottom plates, one of said bottom plates being disposed at an angle of from thirty to thirty-five degrees from the horizontal and the other of said bottom plates being disposed at an angle of from thirty-five to forty-five degrees from the horizontal, side portions for said plates adapted to conform to the rollers of the mill, the top of the discharge end being uncovered and the top of the feed end being provided with a removable cover arranged at an angle of from thirty-five to forty degrees from the horizontal with upward divergence from the bottom plate therebeneath, said side portions being provided with horizontal supporting portions at the top for receiving macerating water supply pipes thereon across the chute, and built-in scrapers mounted at the receiving end of the chute and provided with means for adjusting the same, said scrapers being connected to the adjacent edges of the bottom and cover plates.

JOSEPH MEINECKE.
